UNITED STATES PATENT OFFICE.

FRANK L. JAMISON, OF PITTSBURGH, PENNSYLVANIA.

INGOT-CASTING DEVICE.

1,425,658.

Specification of Letters Patent. Patented Aug. 15, 1922.

Application filed January 6, 1921. Serial No. 435,341.

To all whom it may concern:

Be it known that I, FRANK L. JAMISON, a citizen of the United States, residing at Pittsburgh, in the county of Allegheny and 5 State of Pennsylvania, have invented certain new and useful Improvements in Ingot-Casting Devices, of which the following is a specification.

This invention relates to new and useful 10 improvements in ingot casting devices, and the primary object thereof is to provide a device of the character described, in a manner as hereinafter set forth, with means whereby the formation of the defect commonly known as "piping," due to the shrinkage of the metal during the process of cooling or hardening, is effectively prevented, and under such conditions providing for the 15 economic manufacture of ingots.

20 Further objects of the invention are to provide a device of the character described, which may be used in connection with a mold of the usual construction without alterations thereto, which is simple in its construction and arrangement, strong, durable 25 and efficient in its use, and comparatively inexpensive to manufacture.

To the accomplishment of these and such other objects as may hereinafter appear, the 30 invention consists of the novel construction, combination and arrangement of parts herein specifically described and illustrated in the accompanying drawing, wherein is shown what is now thought to be the best 35 embodiment thereof, but it is to be understood that changes, variations, and modifications in the construction may be resorted to, without departing from the principle or sacrificing any of the advantages of the invention, which come within the scope of the 40 claim hereunto appended.

In the drawing forming a portion of this specification and wherein like numerals of reference designate corresponding parts 45 throughout the several views:

Figure 1 is a vertical sectional view of an ingot casting device in accordance with this invention, with a portion of the mold broken away.

50 Figure 2 is a top plan view thereof.

Figure 3 is a side elevation of the hood member.

Figure 4 is a perspective view of a portion of the burner element, and Figure 5 is a vertical view of a modified form of the device.

Referring in detail to the drawing 1 indicates an ingot mold of the usual construction. The mold is open at its upper end and rectangular in contour, although it is understood that it can be of any desired shape.

60 Mounted on the top of the mold 1 is a rectangularly shaped hollow head 2 which is open at its upper and lower ends forming a passage 3 through the head 2. The passage 3 through the head 2 is tapered to diminish 65 in size toward the upper end thereof to permit of its convenient removal after the molding operation. The width and breadth of the passage 3, throughout is smaller than the width and breadth than the ingot forming 70 chamber of the mold 1.

75 A laterally projecting flange 4 is formed integral with the outer face of the lower end of the head 2, and is provided with a recess 5 on its lower face, forming a depending portion 6 extending into the mold 1 when the head 2 is positioned thereon. The corners of the passage 3 and the lower edge thereof are rounded off to assuage the deteriorating effect of the molten metal there- 80 against.

85 A burner tube 7 entirely surrounds the lower end of the head 2 and is carried on the upper face of the flange 4, but slightly spaced therefrom by resting on the diagonally disposed ribs 8, one of which is positioned at each corner of the flange 4 and formed integrally therewith. A fuel supply pipe 9 communicates with the burner tube 7.

90 The burner tube 7 is spaced from the outer face of the head 2 and is provided with two rows of burner openings 10 and 11, respectively. The former are adapted to project the flame horizontally against the outer face of the head 2, and the latter are adapted to 95 project the flame upwardly in an angular position against the outer face of the head 2.

100 Enclosing the head 2 is a rectangularly shaped hood 13, which is open at its lower end and provided with a vent 14 in its top. A suitable cover plate 15 is provided to close the vent 14 when required. Each corner of the lower end of the hood 13 is formed with a leg 16 which is adapted to engage in a recess 17 provided therefor in each corner of 105 the flange 4 on the top face thereof. One wall of the hood 13, on its lower edge, is provided with a cut-out portion 18 to permit of the passage of the fuel supply pipe 9 there-through. The lower edge of the walls of the 110

hood 13 is tapered, as at 19, to facilitate the passage of air to the burner element to aid combustion.

The outer surface of the head 2 and the 5 inner surface of the hood 13 are equally spaced from each other throughout, forming a heating chamber therebetween.

The inner surface of the hood 13 is preferably provided with a lining or refractory 10 material 20, namely, asbestos cement, or other suitable equivalent.

In the modification shown in Figure 5 of the drawing, all parts of the device are identical in construction as that described 15 above in reference to the preferred form, with the exception of the hood 21 and the position of the burner element 22. In the modified form the hood 21 is provided with an enlarged lower portion 23, which latter 20 is adapted to surround the upper portion of the mold 1. The hood 21 is supported by the legs 24 on the flange 25 in the same manner as in the preferred form. The burner element 22 is carried by hangers 26, one of 25 which is carried by and depends from each corner of the lower end of the enlarged portion 23 of the hood 21.

To close all possible interstices between the head 2 and mold 1, plastic clay 27, or 30 its equivalent, is interposed between the contacting parts.

When casting ingots by the ordinary method a portion of each is rendered useless and cut away due to "piping," that is, to 35 the cavity formed at the top of the ingot due to the shrinkage of the metal during the process of cooling or hardening of the ingot.

By the use of my improved device a perfectly solid ingot is invariably produced in 40 the following manner:

The head 2, hood 13 and the burner element are positioned on the mold in a manner herein described. By use of the burner ele-

ment the head 2 is intensely heated. After 45 the head 2 has been brought to a sufficient heat, the metal is poured into the mold 1 in a sufficient quantity to fill the latter and to partially fill the head 2 also. During the pouring operation and during the first few minutes of the hardening process, the fire 50 from the burner element is kept playing against the head 2 and the vent 14 is open. In this manner the top portion of the poured metal will not be permitted to solidify before the other portions thereof. The excess 55 metal carried in the head 2 is ample to provide for any shrinkage in the main mass of metal, within the mold 1, and "piping," if any will only be in that portion of the metal extending in the head, as is clearly shown 60 at 28, in Figure 1 of the drawing. When the burner element is closed off or inoperative after the pouring operation the vent 14 is closed by the cover plate 15 to confine the generated heat. 65

In the modified form of construction the operation of the device is the same with the exception that in addition to heating the head as described, the top portion of the mold is also heated, but in the normal conditions of practice this method is not essential. 70

What I claim is:

An ignot casting device comprising a head having its lower portion formed with a 75 flange adapted to be seated on the top of a mold body, a hood enclosing and spaced from the head and providing a heating chamber, and a heating element arranged at the lower portion of the chamber, said flange forming the bottom of the chamber, and said hood having legs extending into the said flange. 80

In testimony whereof I affix my signature.

FRANK L. JAMISON.
